UNITED STATES PATENT OFFICE.

FREDERICK A. GALE, OF CHICAGO, ILLINOIS.

METHOD OF RECHARGING BOILERS.

No. 831,336.

Specification of Letters Patent.

Patented Sept. 18, 1906.

Application filed May 26, 1905. Serial No. 262,340.

To all whom it may concern:

Be it known that I, FREDERICK A. GALE, a resident of Chicago, in the county of Cook and State of Illinois, have invented certain new and useful Improvements in Methods of Recharging Boilers, of which the following is a full, clear, and exact description.

The invention relates to replacing the foul water in a locomotive-boiler with fresh or pure water, and designs primarily to provide an improved method whereby the impure water can be blown off and simultaneously replaced by fresh feed-water.

In locomotive practice the period of time consumed in blowing off and recharging the boiler is of importance, because the locomotive is kept out of service during this operation. By filling and blowing off simultaneously it becomes possible to perform this operation quickly and in such a short period that the operation can be frequently performed between trips without interruption in the service of the locomotive, and by occasional replacement during such periods the life of a boiler can be materially extended. By practicing this method frequent washing out of the boiler becomes unnecessary, and when treated water is used periodical replacement suffices to keep the boiler in good condition. The invention further designs to provide an improved method of replacing impure feed-water in a locomotive-boiler with fresh feed-water.

The drawings illustrate apparatus for carrying out the improved method.

Figure 1 is a diagrammatic view showing the pipe connections located in the roundhouse or near the engine-stalls and any other apparatus which may be located at any convenient place. Fig. 2 is a detail view showing the pipe-mains and the manner of connecting the dome-cock of a boiler to the feed-water and blow-off mains.

The improved method contemplates simultaneous blowing-off and filling of the boiler with fresh water in such manner that the impurities in the boiler will be removed during the blowing-off operation. The simultaneous introduction and discharge of fresh superheated water under pressure and discharge of the foul feed-water makes it possible to frequently replace the foul feed-water and remove all solids in suspension in the foul feed-water without material interruption in the service of the locomotive. This method is performed by introducing through the top of

the boiler superheated water under sufficient pressure and of a higher temperature than that in the boiler, while the foul water of lower temperature is blown off through the 60 blow-off cock at the bottom of the boiler. Manifestly the steam in the boiler is saved, and the boiler is recharged so quickly that it can be frequently performed between the trips of a locomotive.

The plant for carrying out the improved method is illustrated in the accompanying drawings, in which the roundhouse is equipped with a series of pipes comprising a blow-off main 10, a feed-water main 11, and a main 12 for washing-water. These extend around the roundhouse and are provided with taps or connections in suitable number, according to the capacity of the roundhouse. Each blow-off connection for the blow-off main 10 comprises a pipe standard or leg 13, connected to the blow-off main, as at 14, and branch pipes 15, connected to the lower end of pipe 13, each of which is provided with a valve 16 for respectively controlling communication 80 between the blow-off main and a locomotive-boiler X at each side of the pipe 13. Pipe 13 is arranged midway between two engine-stalls, so that a locomotive at either side can be blown off through pipe 13 or, if desired, a 85 locomotive can be blown off through both of its cocks 18. A flexible pipe 17 is adapted to connect each branch pipe 15 with the blow-off cock 18 usually provided at each side of the locomotive-boiler. The blow-off water 90 and sediment in the locomotive-boiler will, by reason of the pressure in the boiler, be forced through cocks 18, flexible pipes 17, valves 16, and pipe 13 into the blow-off main. The connections for blowing off steam into the 95 blow-off main (see Fig. 2) each comprise a valve 19, connected to main 10, pipe 20, pipe-standard 21, and a pipe 22, one end of which is adapted to be connected to a valve 23, usually provided in the dome of the boiler. 100 Pipes 21 and 22 are provided with flexible joints 24 for convenience in connecting the dome of the boiler to the blow-off and feed-water mains. When this connection to the dome has been made, the blow-off steam can pass through pipes 22, 21, and 20, valve 19 into the blown-off main 10. The connection comprising pipes 21 and 22 serves also as a filling connection. A pipe 20' is connected to pipe-standard 21 and to a valve 23', which 110 is connected to feed-water main 11. (See Fig. 2.) This connection makes it possible

to introduce feed-water into the boiler through the dome connection. The feed-water main is also connected by a pipe-standard or leg 24 to branches 25, which have terminals adapted to be connected by flexible pipes, such as 17, to the blow-off plugs at the sides of the locomotive. A valve 27 controls supply of feed-water to branches 25, and a valve 28 adjacent one terminal of pipe 15 25 controls passage through one terminal. Valves 32 and 28' control passage of feed-water to the other terminal of pipe 25. Obviously by means of valves 28, 32, and 28' feed-water can be supplied through either or both of the terminals of branches 25 to the boilers adjacent the leg 24.

The wash-out main 12 is connected to supply washing-water to branches 25 by a pipe-standard 29, which is connected to said branches and is provided with a valve 31 for controlling the passage of washing-water to said branches. A valve 32 is arranged between the pipes 29 and 13 to cut off communication therebetween, so that the terminal at one side can be used for refilling while the terminal at the other side can be used for washing. By manipulation of valves 27, 28, 32, and 28' either or both of the terminals of branch 25 can be used for supplying water to a wash-out connection or feed-water to a boiler. Blow-off main 10 conducts the blow-off water in the locomotive-boiler to a pipe 10', which conveys the same to a reservoir B for washing-water. This blow-off water may be utilized in any well-known manner either for heating feed-water or for washing-water.

A superheater E is provided for raising the temperature of the feed-water before it is supplied to the locomotive-boiler. If desired, an exhaust-steam heater A can be used to heat the fresh water before it passes to the superheater E. The superheater is preferably a fuel-heater, but may be of any suitable type. The superheater raises the temperature of the feed-water sufficiently—say to 300° Fahrenheit—so that the water introduced into the top of the boiler will be of higher temperature than that in the boiler, and being of lower specific gravity the fresh water will not readily commingle with the impure water and solids in suspension of lower temperature. Resultantly during the filling and blowing-off operation the fresh water and foul water will remain separated to a great extent. A pipe 45 supplies fresh water to heater A, and the water passes from said heater by a pipe 60 to a steam-pump F, from which said water passes by pipe 61 to the superheater E. Pipe 62 conducts the superheated water from heater E to feed-water main 11 in the roundhouse. A check-valve 63 in pipe 61 prevents backflow of the water under pressure in the feed-water main. The supply of water from heater A to the

superheater and the pressure in the feed-water main 11 and in the superheater are automatically controlled by a "Fisher" governor 64, which controls the operation of force-pump F, so that the desired pressure in the feed-water-supply line will always be maintained. It will be understood that this governor can be regulated so that the desired pressure necessary to cause feed-water to enter the boiler can be established in the feed-water line. Steam for the operation of pump F is supplied by a pipe 65. A small circulating-pipe 66 is connected to one end of the feed-water main 11 and to pipe 60 to maintain circulation in the feed-water line, and whereby the feed-water throughout the supply-line will always be kept at the desired temperature, and thereby avoid a fracture of a part of the boiler, likely to result on injection of cold water. Pipe 45 has direct connection 45' with pipe 60, so that if there is no supply of hot water in reservoir A fresh water can be pumped directly from the supply-main 45 to the superheater.

The improved method is carried out with the apparatus described in the following manner, viz: Hose connection 17 is coupled to the blow-off cock at the side of the boiler, and pipe 22 is connected to the dome-cock 23. Valves 18 and 16 are then opened to discharge the water containing the accumulated solids in suspension, so the solids and the water of the lowest temperature in the boiler will be blown off into main 10, which may conduct the blow-off to any desired point. Simultaneously superheated water, under necessary pressure greater than that in the boiler, will be supplied through the dome connection and into the boiler. The difference in temperature between the superheated feed-water and the water in the boiler will cause the fresh feed-water to remain near the top of the boiler, so that it will not commingle with the impure water and solids near the bottom of the boiler, which will be blown off. To prevent agitation of the water in the boiler to such extent that the impure water will commingle with the hot fresh water, a divider or sprayer *o* may be connected to the dome-cock 23, so that the stream of fresh feed-water entering the boiler will be divided or distributed. Manifestly, then, the impure water with the solids in suspension at the bottom of the boiler will be discharged and replaced by fresh water as the impure water leaves the boiler. For this purpose it is not necessary to bank or put out the fire. The locomotive remains hot during the entire recharging operation, and thus avoids the material change of temperature and resultant expansion and contraction which strain the boiler. By this improved method impure water can be frequently replaced in a very short period, and by occasional replacement the life of a loco-

motive is materially lengthened without washing out the locomotive-boiler.

The particular apparatus illustrated does not form any part of the present invention, and for a fuller description thereof reference may be had to my application filed April 21, 1905, Serial No. 256,711.

Manifestly the invention is not to be understood as restricted to the particular details of practice set forth, but may be modified within wide limits without departing from the spirit and scope of the invention.

Having thus described the invention, what I claim as new, and desire to secure by Letters Patent, is—

1. That improvement in cleaning locomotive-boilers which consists in blowing off the impure feed-water from the boiler, and simultaneously forcing fresh hot water under

pressure into the boiler to displace the blow-off.

2. That improvement in cleaning locomotive-boilers which consists in blowing off the impure feed-water from the boiler and simultaneously forcing into the boiler fresh water under greater pressure and of a higher temperature than that in the boiler to displace the blow-off.

3. That improvement in the art of filling locomotive-boilers which consists in forcing fresh water under pressure and of a higher temperature than that in the boiler, into the boiler, and simultaneously discharging the impure water from the boiler.

FREDERICK A. GALE.
